Alexander Burkes, New York, N. Y., assignor to
Plastic Innovations, Inc., New York, N. Y., a
corporation of New York

Application November 26, 1949, Serial No. 6,269

Term of patent 14 years

(Cl. D34—4)

To all whom it may concern:

Be it known that I, Alexander Burkes, a citizen of the United States, residing at New York, in the county of New York and State of New York, have invented a new, original, and ornamental Design for an Inflatable Toy Roly-Poly or the like, of which the following is a specification, reference being had to the accompanying drawing, forming part thereof.

In the drawing

Fig. 1 is a side view of an inflatable toy roly-poly or the like showing my new design;

Fig. 2 is a front view thereof;

Fig. 3 is a rear view thereof; and

Fig. 4 is a top view thereof.

I claim:

The ornamental design for an inflatable toy roly-poly or the like, substantially as shown.

ALEXANDER BURKES.
